United States Patent Office.

FRANK J. ROTH, OF SCHENECTADY, NEW YORK.

Letters Patent No. 77,532, dated May 5, 1868; antedated April 22, 1868.

IMPROVEMENT IN PISTON-PACKING.

The Schedule referred to in these Letters Patent and making part of the same.

TO ALL WHOM IT MAY CONCERN:

Be it known that I, FRANK J. ROTH, of Schenectady, State of New York, have invented certain new and useful Improvements in Piston-Packing; and I declare the following to be a full, true, and exact description of the same, reference being had to the accompanying drawings, and to the letters of reference marked thereon,

Figure 1 represents an end view of my invention, with the follower removed.

Figure 2 is a section view of the same.

Figure 3 is a plan view of the wedge to which the spring is attached.

Figures 4, 5, and 6 represent different views of the packing-rings.

This piston-packing is constructed to pack the cylinder with spring and steam combined.

The body of the piston is composed of spider A, follower B, and inner ring C, and when screwed together will form a solid body.

The packing-rings D are made so as to freely slip over the inner ring C, and are turned as near the size of the cylinder as possible, and are constructed with a projecting edge on their outer space, as seen in fig. 4. This projection can be varied to correspond with the pressure of steam in the cylinder. These rings are each divided into three different pieces or sections, and are held together by means of a dowel-pin, as seen in fig. 5. All of the joints are fitted neatly together, with the exception of the lower ones, which are held apart by means of a V-shaped wedge and spring, as seen in fig. 3. This wedge F and spring G can be used in three different ways, and for three different purposes: first, to keep the packing expanded; second, to keep all other joints in close contact with one another; and third, to shut off all communication of steam from the inner surface, and to support, in combination with the steam, the weight of the piston. In engines where the weight of the piston is supported by the piston-rod, as in vertical-running engines, the wedges have to be placed in opposition to one another, so as to keep the piston as much as possible in the centre.

The rings E are fitted loosely over the inner ring C, but in such a manner as not to allow it much play. The inner face is turned so as to form a steam-joint, with corresponding face of ring D, while the outer edge is bevelled off, as seen in fig. 1, so as when acted upon by steam it is forced tightly against ring D. This ring E answers two important purposes: first, packing of this kind can be applied to any piston without the alteration of the spider and follower; second, it acts as packing to pack-ring D, no matter how loose it may be. The rings E can be bored out somewhat larger than inner ring C, and cut out sufficiently, so that when acted upon by the steam they will close upon the inner ring C, so as to prevent any steam from passing into the packing-rings.

There is but very small pressure required to keep packing-rings steam-tight against the surface of the cylinder, and all pressure above that is disadvantageous, first, in reduction of power, and second, in unnecessary wear of the cylinder and packing.

The steam passes over follower or spider, under the projecting edge of ring D, and forces those rings gently against the inner surface of the cylinder; and at the same time forces rings E against the face of ring D, and by this means prevents any steam from passing into the other rings.

Having thus described my invention, what I claim, and desire to secure by Letters Patent, is—

The side-rings E and packing-rings D, when combined substantially in the manner set forth.

In testimony that I claim the above, I affix my signature in presence of two witnesses.

FRANK J. ROTH.

Witnesses:

CHARLES ROTH,

ANDREW SCHINNERNER.
